Primary Examiner—Robin V. Taylor
Assistant Examiner—Lavone Tabor(57) **CLAIM**

The ornamental design for a bristle for a brush, as shown and described.

DESCRIPTION

FIG. 1 is a perspective view of a bristle for a brush showing my new design;

FIG. 2 is a front elevation view thereof;

FIG. 3 is a side elevation view thereof;

FIG. 4 is a top plan view thereof; and,

FIG. 5 is a bottom plan view thereof.

The bottom end of the bristle is shown broken away to indicate indeterminate length.
